(57) CLAIM

The ornamental design for a valve stem cap with display dimple, as shown and described.

DESCRIPTION

FIG. 1 is a front elevational view of a valve stem cap with display dimple, showing my new design;

FIG. 2 is a bottom plan view thereof;

FIG. 3 is a top plan view thereof; and,

FIG. 4 is a perspective view thereof.

The broken lines in the drawings depict environmental structure, which forms no part of the claimed design.
